ATTORNEY

UNITED STATES PATENT OFFICE.

JOHN H. HAMBY, OF CUMMING, GEORGIA.

BOLL-WEEVIL CATCHER.

Application filed May 12, 1923. Serial No. 638,567.

To all whom it may concern:

Be it known that I, JOHN H. HAMBY, a citizen of the United States, residing at Cumming, in the county of Forsyth and

5 State of Georgia, have invented certain new and useful Improvements in Boll-Weevil Catchers, of which the following is a specification, reference being had to the accompanying drawings.

10 This invention relates to boll weevil catchers or the like and more particularly to a device of this character having positively driven means for removing the weevil from the plants as the device is moved along the 15 row, together with means for collecting the weevil thus removed.

An important object of the invention is to provide a device of this character including striking elements which are adjustable 20 to thereby permit the device to be employed with plants of varying sizes.

A further object of the invention is to provide a device of this character having collecting pans mounted so that they are 25 readily shifted during the operation of the device to move them toward or away from the stalks of the plants upon which the device is operated.

These and other objects I attain by the 30 construction and arrangement shown in the accompanying drawings wherein for the purpose of illustration is shown a preferred embodiment of my invention and wherein like reference characters designate like parts throughout.

In the drawings:—

Figure 1 is a side elevation of a boll weevil catcher constructed in accordance with my invention;

40 Figure 2 is a plan view thereof;

Figure 3 is an end elevation thereof;

Figure 4 is a detailed sectional view showing the pan mounting employed;

45 Figure 5 is a perspective view showing the connection and mounting of the pan;

Figure 6 is a view of an adjustable bearing employed for the vertical rollers; and

Figure 7 is a detailed view showing the mounting of the horizontal roller;

50 Referring now more particularly to the drawings, the device includes an inverted U-shaped frame comprising longitudinally extending top members 10 connected at their ends by transversely extending members 11 and intermediate their ends at their approxi-

member 12. Depending from the corners of the frame thus formed are vertical members 13, the vertical members at the same side of the machine being connected at their 60 lower ends by longitudinally extending frame members 14 upon which are rotatably mounted supporting wheels 15. The vertical members are suitably braced as at 16 to the upper frame members and as at 17 to the 65 lower frame members. At each side of the machine and immediately below the longitudinally extending members 10 of the upper frame, the vertical members 13 are connected by longitudinally extending supports 18. Each support 18 at the approximate center thereof is connected by a vertically extending member or strut 19 with the corresponding lower frame member 14. 70

Upon the supporting members approximately centrally thereof are mounted bearings 20, each receiving one end of a short shaft 21, the opposite end of which is supported by a bearing 22 depending from the central cross member 12 of the upper frame. 75

Upon each of the shafts 21 a roller 23 is mounted and the outer ends of these shafts are provided with sprockets 24 connected with sprockets 25 secured to a supporting wheel 15 at the corresponding side of the 80 machine, by a chain 26 so that these shafts and their rollers are driven as the device is moved over the ground. Rearwardly of the shafts 21 the upper and lower frame members 10 and 14 are each provided with bearing members 27 adjustable transversely of the machine, these bearing members rotatably receiving the ends of a shaft 28 and mounted thereon a roller 29 provided with curved striker fingers 30. From each of the 85

rollers 23 a drive belt 31 extends to the corresponding roller 29. Secured at their lower ends to the struts 19 and at their upper ends to the longitudinally extending supports 18 are guides 32 having formed therein arcuate 90

slots 33 receiving rollers 34 forming a mounting for bearings 35 in which are mounted the ends of a shaft having a roller 36 thereon. The curvature of the slot 33 has as a radius the center of one of the 95

shafts 21 and the roller 36 is connected with the roller 23 of this shaft by a belt 37. The roller 36 is provided with striker fingers 38 for engagement with the plants upon which the device is operated. To one of the 100

55 bearings 35 is secured a link 39, the opposite end of which is pivotally connected with one end

of a rod 40 pivoted intermediate its ends upon the upper frame, as indicated at 41. The opposite end of this lever is connected through a link 42 with one end of a lever 43 which coacts with a segment 44, by means of which it may be held in adjusted position. By shifting the segment lever 43 the roller 36 may be vertically adjusted to thereby regulate its height from the ground 10 over which the device is passing.

The front and rear cross members 11 of the upper frame are provided with aligned centrally disposed guides 45 in which is slidably disposed a rod 46, the rear end of 15 which is provided with an operating handle 47. Adjacent each end of the frame, each of said side members 10 has directed therethrough a shaft 48. Between the horizontal members 10 and 18 the shaft 48 is directed 20 through the arms 49 of the U-shaped yoke Y, the yoke being rotatable upon the shaft and having the arms thereof directed inwardly. Upon the upper ends of the shafts 48 are rotatably mounted the outer ends 25 of links 50, the inner ends of which are provided with slots 51 slidably receiving studs 52 carried by the reciprocatory rod 46, the links 50 at corresponding ends of 30 the side members preferably engaging the same stud of the reciprocatory rod. To these rods, at points spaced from the outer ends thereof, are secured the upper ends of supports 53 which extend through and are secured to the inner ends of the arms 49 35 of the yokes Y and to which are secured at the lower ends thereof insect receiving pans 54 adapted for the reception of an insecticide and to receive weevil knocked from the plants of a row upon which the 40 device is operated by the striker members 30 and 38, of the rollers 29 and 36. It will be seen that by longitudinal shifting of the rod 46 the positions of the supports 53 with respect to the sides of the frame 45 may be adjusted, the lower ends of these supports swinging outwardly from or inwardly toward the sides of the frame, thus moving the pans 54 toward or away from one another. The outer edges of these pans 50 are connected with the frame members by means of flexible strips 55 of any suitable material which will permit movement of the pans toward or away from one another and at the same time prevent the passage 55 of insects knocked from the plants between the frame member and the outer edges of the pans. The frame, at the top and sides thereof, is covered by a suitable screening 56 which likewise serves to prevent the escape of insects.

From the foregoing it will be seen that the rollers 29 may be readily adjusted toward one another, thus enabling the device to be regulated so that the strikers 30 of the rollers will properly engage the sides

of the plants, whether these plants be young and small or mature and well grown. Similarly, by adjustment of the roller 38, the tops of the plants may be engaged without regard to the height thereof. The mounting of the pans is particularly important, due to the fact that it is desirous that at all times when possible the edges of the pans be directly engaged with the stalks of the plants of the row upon which the device is operated. It will be obvious that when so engaged any of the plants which are staggered or misaligned will be engaged by the pans and in all probability broken, or in any event damaged. The adjustability of the pans permits the operator at any time during the operation of the device to shift the pans inwardly or outwardly to accommodate inequalities or irregularities in planting. It will be obvious that the structural details of the device as hereinbefore set forth are capable of some change and modification without materially departing from the spirit of my invention and I accordingly do not limit myself to such specific structure as hereinbefore set forth except as hereinafter claimed.

What is claimed is:—

1. In a boll weevil catcher, a frame adapted to be moved along a row of plants to receive the plants between the sides thereof, vertical rollers arranged at opposite sides of the frame and adjustable toward and away from each other, a horizontal roller extending transversely of the frame and adjustable toward and away from the ground, striker arms carried by said rollers, and means operated by the movement of the frame along the row of plants for rotating said rollers.

2. In a boll weevil catcher, a frame adapted to be moved along a row of plants to receive the plants between the sides thereof, vertical rollers arranged at opposite sides of the frame and adjustable toward and away from each other, a horizontal roller extending transversely of the frame and adjustable toward and away from the ground, striker arms carried by said rollers, means operated by the movement of the frame along the row of plants for rotating said rollers, pans carried by said frame and adapted to receive weevil knocked from the plants by the arms of the rollers, and means operable during movement of the device along the row of plants for shifting said pans toward and away from one another.

3. In a boll weevil catcher, a frame adapted to be moved along a row of plants to receive the plants between the sides thereof, vertical rollers arranged at opposite sides of the frame and adjustable toward and away from each other, a horizontal roller extending transversely of the frame and adjustable toward and away from the ground,

striker arms carried by said rollers, means operated by the movement of the frame along the row of plants for rotating said rollers, pans carried by said frame and adapted to receive weevil knocked from the plants by the arms of the rollers, means operable during movement of the device along the row of plants for shifting said pans toward and away from one another, a screen covering for the top and sides of said frame, and a flexible connection between the outer edges of said pans and the sides of the frame for sealing the space therebetween.

4. In a boll weevil catcher, a frame adapted to be moved along a row of plants to receive the plants between the sides thereof, vertical rollers arranged at opposite sides of the frame and adjustable toward and away from each other, a horizontal roller extending transversely of the frame and adjustable toward and away from the ground, striker arms carried by said rollers, means operated by the movement of the frame along the row of plants for rotating said rollers, pans carried by said frame and adapted to receive weevil knocked from the plants by the arms of the rollers, means operable during movement of the device along the row of plants for shifting said pans toward and away from one another, including supports for said pans secured to the pans at their lower ends, vertically pivoted arms associated with each support and through the free ends of which the supports are directed, a pivoted link associated with each support and to which the upper end of the support is secured, and means carried by the frame for simultaneously shifting all of said links.

5. In a boll weevil catcher, a U-shaped frame adapted to be moved along a row of plants, vertically pivoted U-shaped yokes carried by the frames at the sides thereof, supports having their upper ends directed through the free ends of the yokes, pans se-

cured to the lower ends of said supports, links pivoted to the frame at their ends and secured to said supports inwardly of their ends, a bar reciprocable longitudinally of the frame, and a connection between said bar and each of said links whereby the links are oscillated when the bar is reciprocated, and means associated with the frame for knocking weevil from plants upon which the frame is being employed into the pans thereof.

6. In a boll weevil catcher, a frame adapted to be moved along a row of plants to receive the plants between the sides thereof, vertical rollers arranged at opposite sides of the frame and adjustable toward and away from each other, a horizontal roller extending transversely of the frame and adjustable toward and away from the ground, striker arms carried by said rollers, means operated by the movement of the frame along the row of plants for rotating said rollers, pans carried by said frame and adapted to receive weevil knocked from the plants by the arms of the rollers, means operable during movement of the device along the row of plants for shifting said pans toward and away from one another, including supports for said pans secured to the pans at their lower ends, vertically pivoted arms associated with each support and through the free ends of which the supports are directed, a pivoted link associated with each support and to which the upper end of the support is secured, and means carried by the frame for simultaneously shifting all of said links, a cover for said frame, and a connection between the outer edge of each pan and the adjacent arm of the frame permitting adjustment of the pan toward and away from the frame and sealing the space between the pan and frame.

In testimony whereof I hereunto affix my signature.

JOHN H. HAMBY.
